UNITED STATES PATENT OFFICE.

JOHN D. McMILLAN, OF ALHAMBRA, CALIFORNIA.

HARROW.

No. 900,116.

Specification of Letters Patent.

Patented Oct. 6, 1908.

Application filed March 21, 1908. Serial No. 422,502.

To all whom it may concern:

Be it known that I, JOHN D. McMILLAN, a citizen of the United States, residing at Alhambra, in the county of Los Angeles and 5 State of California, have invented certain new and useful Improvements in Harrows, of which the following is a specification.

This invention relates to spring-tooth harrows, and the principal object of said 10 invention is to provide reliable and efficient means for quickly adjusting the throw of the lever which controls the depth of penetration of the spring teeth of the harrow.

Spring-tooth harrows as at present constructed, are provided with a lever for rocking the tooth-bars to give the teeth the required penetration and to raise them out of the ground when the harrow is being drawn to and from the field of operation. 15 This lever is rigidly bolted to a yoke or casting connected to the tooth-bars by a bolt, and a sector rack is provided for holding the lever in place when it is thrown into the required position. The throw of this lever 20 is thus limited in its movement relatively to the sector rack, and this throw of the lever is sufficient when the harrow is new and the teeth have not become shortened or worn away. There being no means of adjustment of this lever relatively to the tooth-bars, when the teeth become worn, the entire harrow must be readjusted, and this is 25 an expensive operation.

My invention embodies simple and inexpensive means for connecting the tooth-bars to the lever in such manner that the tooth-bars may be easily and quickly shifted relatively to throw of lever. In its broadest aspect my invention involves novel means 30 for adjusting the regulating lever of a spring-tooth harrow relatively to the tooth-bars to compensate for the wear of the teeth.

The objects and advantages referred to 35 may be attained by means of the construction illustrated in the accompanying drawing in which,—

Figure 1 is a side elevation of a spring-tooth harrow embodying my improvements—Fig. 2 is a detail side view of my 40 invention shown attached to a tooth-bar and connected by link *d* to the lower end of the regulating lever, the tooth-bar being shown in section—Fig. 3 is a view taken at right angles to Fig. 2.

Referring to the accompanying drawing 55 for a more specific description of my invention, the numeral 1 designates the runners; 2 the bearings in which the tooth-bars 9 are journaled to rock; 4 are the spring teeth secured to the tooth-bars; 5 is the connecting rod, and 6 and *d* are the links which connect the tooth-bars to the connecting rod. These parts may be of the usual or any suitable construction.

As usually constructed the links 6 and *d* 65 are connected at their lower ends to a yoke or a casting bolted to the tooth-bars—but not adjustably.

In accordance with my invention, the links 6 are connected by means of bolts 7 and 8 to 70 an adjusting device A, forming my invention, and comprising a yoke *a*, which partially surrounds the tooth-bar 9 and which is firmly connected thereto by means of the bolts 10.

The adjusting device A is provided with a 75 wide flat lug provided with bolt holes through which the bolts 7 and 8 pass, and additional adjusting holes, *b* and *c* for the links 6.

The regulating lever, B, is integral with 80 link *d*, which has a flattened angularly bent end pivoted to the connecting rod 5. The lower end of the link *d* is provided with bolt holes for the bolts *g* and *h*. The adjusting device A for the lever B is identical in construction with those to which the links 6 are connected, and is provided with adjusting holes *b* and *c*.

A sector rack 11 is secured to the connecting rod 5, and the spring pawl 12 engages 90 the teeth of said rack to hold the spring teeth 4 in the required adjustment.

When the ends of the teeth 4 have been worn away by constant use, the links 6 and *d* to which the lever B is bolted may be adjusted as follows: The bolts 8 are removed and the bolts 7 loosened to serve as pivotal points between the links 6 and the adjusting device A. The bolts 8 are then passed through the same hole in the links and 100 through holes *b* or *c* in the adjusting device. The link *d* is adjusted in a similar manner, as will be understood.

From the foregoing it will be obvious that my invention provides for a quick adjustment to compensate for the wear of the teeth; that the cost of the adjusting device is but slightly greater than the yoke or casting 105

which it displaces, and much time, labor and expense are saved by its use.

Having thus fully described my invention what I claim and desire to secure by Letters-Patent is:—

In a spring-tooth harrow, and in combination with pivoted tooth-bars and a connecting rod, an adjusting lever, links, and an adjusting device comprising a yoke for con-

nection to a tooth-bar, and a lug having adjusting holes for the links.

In testimony whereof I affix my signature, in presence of two witnesses.

JOHN D. McMILLAN.
